ARBA PERRY, OF CHICAGO, ILLINOIS.

GAME APPARATUS.

1,146,733.

Specification of Letters Patent. Patented July 13, 1915.

Application filed December 1, 1913, Serial No. 803,902. Renewed May 15, 1915. Serial No. 28,484.

To all whom it may concern:

Be it known that I, ARBA PERRY, a citizen of the United States, residing at Chicago, in the county of Cook and State of Illinois, have invented a new and useful Game Apparatus, of which the following is a specification.

The object of my invention is to produce the equipment by means of which may be played a game having the essential characteristics of the pocket billiard game commonly known as "Kelley pool", so far as the same may be possible in the absence of a pocket billiard table, the sixteen balls and the necessary cues.

The equipment for my game is illustrated in the accompanying drawing which shows the individual pieces of the equipment.

The equipment comprises fifteen cards A bearing on their faces the numbers 1 to 15, inclusive, or otherwise designated to indicate the fifteen balls which are commonly used upon a pocket billiard table. The exact manner in which these cards shall be separately designated to indicate the values 1 to 15 is, of course, immaterial. Additional cards B are provided and suitably designated as "scratch" cards. The exact number of these cards B is not especially material, although it is desirable that enough of the cards be provided to give to the game a sufficient hazard, without, however, increasing the hazard too greatly. I find that ten of these cards is a satisfactory number. These cards B indicate what, in "Kelley pool", would be the delivery of the cue ball into one of the pockets of the table. I also provide a multiplicity of cards C which are blank, these cards corresponding to the condition in "Kelley pool" where the player has shot the cue ball without accomplishing the deposit of any object ball into a pocket. The exact number of these cards C is also immaterial, but it is my experience that fifteen of these cards is a satisfactory number. I also provide fifteen numbered checks, buttons, or other convenient tokens D which are numbered consecutively from 1 to fifteen, or designated to correspond with the designations of the fifteen cards A.

Any number of persons can play the game at one time and these players are grouped at a table. The cards A, B and C are shuffled together and placed face down in the center of the table and the numbered checks D are either placed in a receptacle where their

designations cannot be seen or placed face down on the table and each player draws one of these tokens D and places it, number up, before him. Any player may be selected 60 to lead off but a convenient way of determining this is to give the person drawing the lowest numbered token the first play. The score is kept in any suitable manner, either by count or by the use of valued counters, 65 such, for instance, as ordinary "poker chips", and before the play starts each player contributes one point or counter to a general fund. The first player thereupon draws one card from the top of the deck and 70 places it face up beside the pack. If he draws a blank or card C this blank indicates a miss and the play passes to the next player. If and when one of the cards B is drawn, a scratch is indicated and a point (or more 75 if that has been agreed upon by the players) or a counter is contributed to the general fund, and, by previous agreement, the drawing of a scratch may be considered either as a miss, whereupon play passes to the next 80 player, or the original player may continue until he draws a blank card. Whenever the player turns one of the cards A, the exposed tokens D are examined and if the symbol upon the drawn card corresponds 85 to the symbol upon the token before any other player, that other player will increase the score of the player who has turned the card by an agreed number of points, or counters, and the player who has thus been 90 required to contribute is "put out" and must either discontinue play for the game or, at the option of the players, he may be permitted to draw a new token D and place it before him upon contribution to the general fund of an agreed number of points or 95 counters. Should this player who has been put out draw from the remaining tokens D a number which has been previously exposed in the play of the cards A, he will continue 100 to draw from the tokens D until he exposes a symbol which has not been previously exposed in the play of that game. The determination as to continuance of drawing from the tokens A is to lie wholly with the 105 memory of the player who is drawing and the previously played cards cannot be searched to determine this question. If the drawing player, after drawing a new token D should declare that that particular token 110 had had its corresponding card A previously exposed and should start to draw another,

any other player may demand a view of the previously played cards A, B and C and if it be found that the rejected token D has in fact no counter part in the played cards

- 5 5 A, the score of the challenging player will be increased by an agreed number of points by the drawing player who has been challenged. If the active player exposes a card A bearing the symbol corresponding to that
- 10 10 upon the token D which lies before him, he wins the game, play for the game is discontinued, and his score is increased by the common fund which has been previously provided as described.

- 15 15 Should the situation arise wherein all the players are put out, then a "double header" is created; the cards are reshuffled, the tokens D redistributed; and each player again contributes to the general fund which
- 20 20 is allowed to remain, and this condition is repeated from game to game until the game is won in the manner previously described.

I have designated my improved game as "Kard Kelley".

- 25 25 It is, of course, readily apparent that in order to maintain the analogy with the pocket billard game known as "Kelley pool", the cards A and the tokens D should be fifteen in number, but it will also be readily
- 30 30 apparent that the variation in this number would not change the character of the game or the equipment. The fundamental characteristic of the equipment consists in a pack of cards comprising groups A, B
- 35 35 and C, and token D corresponding in number and designation with the number and designation of the cards in group A.

- 40 40 It will be readily understood that the physical character of the cards and the character of the backs may be varied to a considerable extent, just as ordinary playing-cards are varied, and that the complete apparatus may be either incased in a common telescope case or in any other suitable
- 45 45 manner convenient for sale and storage.

I claim as my invention:

1. A game apparatus comprising a deck of cards embodying three groups, and a

Copies of this patent may be obtained for five cents each, by addressing the "Commissioner of Patents, Washington, D. C."

group of tokens, the cards of one group being consecutively individualized and the 50 cards of the other two groups being group designated, and the tokens corresponding in number and individualization to the first-mentioned group of cards.

2. A game apparatus comprising a plurality of elements indistinguishable from each other upon one face and distinguishable from each other in three groups upon the other face, the elements by their said distinguishing faces being group-distinguished in two of the groups, and in the third group being not only group-distinguished but also separately individualized, and a fourth group of elements readily distinguishable at all times from the said plurality of elements individualized in correspondence with the individualization of the elements of the third group.

3. A game apparatus comprising a deck of cards distinguishable in three groups, the 70 cards of the first group each indicating a blank; the cards of the second group each indicating a scratch; the cards of the third group being fifteen in number and individualized by the numbers 1 to 15; and a set 75 of tokens individualized to correspond in number and individualization with the third group of cards.

4. A game apparatus comprising a deck of cards distinguishable in three groups; the 80 cards of the first group each indicating a blank; the cards of the second group each indicating a scratch; the cards of the third groups individualized; and a set of tokens individualized to correspond in number and 85 individualization with the third group of cards.

In witness whereof, I have hereunto set my hand at Chicago, Illinois, this 28th day of November, A. D. one thousand nine hundred and thirteen.

ARBA PERRY.
